UNITED STATES PATENT OFFICE.

PAUL GAY, OF TRION, GEORGIA.

THERMOSTATIC CIRCUIT BREAKER.

Application filed May 23, 1921. Serial No. 471,577.

To all whom it may concern:

Be it known that I, PAUL GAY, a citizen of the United States, residing at Trion, in the county of Chattooga and State of Georgia, have invented certain new and useful Improvements in Thermostatic Circuit Breakers, of which the following is a specification, reference being had to the accompanying drawings.

This invention relates to automatic stops, and particularly to a stop designed for use on internal combustion engines, acting to stop the engine when the engine has become overheated or when the temperature of the engine has risen to a predetermined degree.

The general object of this invention is to provide a stop of this character which will act to stop the engine by interrupting the ignition circuit of the engine or which may be used to interrupt a lighting circuit (in case it be desired merely to give a signal to the driver) when the car becomes overheated, that is when the temperature of the car has risen to a predetermined degree.

A further object is to provide a mechanism of this kind wherein the breaking or closing of the circuit is controlled by a thermostat mounted in intimate conjunction with the engine or any other part which it is desired to prevent from overheating.

And a further object is to provide a construction of this character which will keep the switch in the electric circuit open until the engine cools to a predetermined degree and during this time preventing the engine from being operated.

Another object is to provide a stop of this character so constructed that it may be set or adjusted to stop the engine at any given degree of heat, and which can be set or adjusted to a point where it will not have any effect on the engine in case of bad connection.

And another object is to provide an automatic stop which will not prevent the engine or automobile from delivering its full power or speed under normal conditions and will not affect the engine in any way until the same is overheated.

Still another object is to provide a device of this character which may be readily applied to all makes of automobile engines and connected in the ignition circuit thereof or in the lighting circuit thereof, and which may be operated either by heat from the engine itself from a bearing or from any

other point where overheating would be dangerous for the engine.

Other objects will appear in the course of the following description.

My invention is illustrated in the accompanying drawings, wherein:

Figure 1 is a plan view of my improved engine stop, the glass 42 and the ring 43 being broken away;

Figure 2 is a top plan view with the plate 15 and the parts carried thereby removed to show the thermostat;

Figure 3 is a face view of the member 17;

Figure 4 is a fragmentary sectional view of the plate 15 and the strip 36, the contact carrier being shown in elevation;

Referring to these drawings, it will be seen that my device comprises a casing 10 having a back plate 11 preferably larger than the casing and forming a base, this back plate being provided with the preferably tangential projecting ear 12 having the elongated aperture 13. By elongating this aperture, the device may be readily applied to the engines and motors of different sizes and particularly to the bolt known as the block bolt. This block bolt is run through this hole to bolt my device to the block of the engine, thus bringing the stopping device in direct contact with the main part of the engine that is liable to overheat. The back plate 11 is formed with a plurality of openings 14 illustrated as three in number, and disposed within the wall of the casing 10 is a front plate 15 upon which the switch scale and other like parts are mounted.

Between this plate 15 and the back plate 11 and within the casing 10 there is mounted a thermostat which operates a shaft 16 mounted in suitable bearings in the back case and extends out through the front plate. As illustrated, this shaft carries upon it a crescent-shaped member 17, one horn or arm of which is engaged by a resilient strip 18 which is attached to the wall of the casing at 19, and the other arm of which is engaged by a strip 20 engaged with the wall of the casing at 21. These strips are formed of resilient material and the strip 18 has its free end move toward the left in Figure 2 upon a reduction in temperature, while the strip 20 moves to the right in Figure 2 upon an increase in temperature. Thus it will be seen that the shaft 16 will be given a counterclockwise oscillation upon an increase in temperature. It will be noted that

two of the openings 14 are elongated and disposed immediately beneath the resilient strips 18 and 20, while an opening is disposed between these resilient strips so that the temperature of the engine block or other part will directly affect these thermostatic strips. I do not wish to be limited to the use of two thermostatic strips, as only one may be used, the strip 18 acting as a spring, and indeed I do not wish to be limited to this particular construction of thermostat, as any other desired construction of thermostat might be used within the space between the back plate 11 and the front plate 15.

15 The shaft 16 extends through the notch or opening 22 in the front plate 15 or through any other suitable aperture and is provided with the depending hand 23 which carries a head 24 of insulated material at its extremity. Mounted upon the face of the plate 15 and preferably slidably mounted thereon for adjustment is an insulating block 25 which carries upon it an outwardly projecting contact 26 and a contact spring 27. This spring is approximately U-shaped and is attached to or forms part of a plate 30, attached to the insulating block 25, the spring extending downward from this plate 30 and then upward in resilient engagement with the contact 26, then upward above this contact into the path of movement of the block 24 on the pointer or hand 23. The resiliency of the contact 27 holds this contact in electrical engagement with the contact 26, but when the extremity of the hand 23 strikes this contact 27, it forces it away from the contact 26 and breaks the electrical engagement between these contacts. The contact 26 is electrically connected by the insulated wire 31 to an insulated binding post 32, which in turn is connected in the ignition circuit of the engine. The plate 30 which supports the contact finger 27 is connected by an insulated wire 33 to the insulated binding post 34, and this binding post in turn is electrically connected in the ignition circuit of the engine. Thus so long as the finger 27 is against the contact 26, the ignition circuit is completed, but if the pointer 23 under the actuation of the thermostat moves the finger 27 away from the contact 26, the circuit is broken and the engine comes to a stop. The finger 27 under these circumstances will be held away from the contact 26 just so long as the engine is heated above a certain temperature, but when the engine cools below a certain temperature, the thermostat will cause the hand 23 to move to the left in Figure 1, thus causing the finger 27 to again contact with the contact 26 and complete the circuit, and the engine will once more start up.

60 As before remarked, it is advisable to have the insulated block 25 slidably mounted for adjustment across the face of the plate 15. To this end, I have illustrated the sliding block as being mounted upon a plate 35 which is slidably mounted upon the strip 36, and I have illustrated the plate 15 as carrying a transversely extending strip 36 forming a track and the plate 35 as being formed with ears 37 extending inward beneath this track. I do not wish to be limited to this construction, however. Also attached to the plate 35 is a traveling nut 38 which is formed of a screw-threaded lug, and through this screw-threaded lug passes an adjusting screw 39 which, at one end at least, extends out to the exterior of the casing 10 and is provided with a head 40 whereby it may be readily manipulated and set. Preferably this head 40 is so constructed that it will require a screw-driver or like implement to rotate it in order that this screw 39 may not be turned accidentally.

65 Disposed upon the base of the plate 25 and beneath the finger 27 is a transversely extending scale 41, and by rotating the screw 39 the sliding carrier which carries the contacts 26 and 27 may be adjusted with reference to this scale, the finger 27 forming an index pointer which coacts with the scale or graduations. It will be obvious now that the further over toward the right that the slide is moved, the higher will be the temperature necessary in order for the pointer 23 to contact with the finger 27 and break the ignition circuit, and that the further toward the left the slide is moved, the less increase in temperature will be necessary in order to cause the pointer 23 to break the circuit. The slide is graduated in degrees, as for instance from 100° to 150°, there being graduations indicating every 100° and every 50°, and thus it is an easy matter to adjust this automatic stop so that it will break the circuit through the engine when the temperature of the engine block or other part has risen to the predetermined degree.

70 I do not wish to be limited to any particular circuit in which this device may be connected, but I contemplate the binding post 34 as being connected to the breaker box or magneto post of the engine, while the wire from the post 32 may be connected to the induction coil. This wiring is, of course, used where the engine uses a magneto for generating the electricity for the ignition circuit, but is purely illustrative of one application of this device, as this wiring might be readily changed.

75 The casing is, of course, provided with a glass pane 42 held in place in any suitable manner, as by a ring 43, thus permitting the scale 41 to be read and the sliding block carrying the contacts to be adjusted. It will be noted that the contact 27 constitutes a resiliently actuated switch projecting into the path of movement of the hand 23.

23, this switch being shifted out of its circuit closing position by the hand 23 and being resiliently urged to its circuit closing position.

While I design this device to be used in connection with an ignition circuit of an automobile in order to provide an automatic stop which will positively stop the engine when a certain temperature has been reached, it is obvious that the breaking of the 10 circuit might cause a certain signal to be given whereby the driver is made aware of the fact that the engine is overheated, and it is obvious also that the same mechanism might be used to complete a circuit 15 through a signal when the temperature had risen to a predetermined degree instead of breaking the circuit through the signal by so forming the finger 27 that it would be normally out of contact with the contact 26 20 and causing the pointer 23 to close the finger against the contact 26 when the predetermined temperature was reached. Neither do I wish to be limited to the details of construction or arrangement of parts as illustrated, as these might be varied in many 25 ways without departing from the spirit of the invention.

I claim:—

A thermostatic circuit closer of the character described comprising a casing, a shaft 20 disposed within the casing, a rocker mounted upon said shaft and having extensions projecting toward each other, a pair of thermostatically shiftable elements mounted upon the casing at one end and at their free 25 ends engaging the inwardly projecting portions of said rocker whereby upon an expansion of said elements the rocker will be shifted in one direction and upon a contraction of the elements the rocker will be 40 shifted in the other direction, a hand carried upon said shaft, a slide, a yieldable contact mounted upon the slide for movement therewith and constituting a pointer, a scale with which said pointer coacts, said contact being disposed in the path of movement of the hand, a fixed contact with which the first named contact normally engages, 45 conducting members connected to said contacts, and means for adjusting the slide. 50

In testimony whereof I hereunto affix my signature.

PAUL GAY.
